UNITED STATES PATENT OFFICE.

ZOE ARMSTRONG, OF McPHERSON, KANSAS.

DESIGN FOR A PAN.

48,095.

Specification for Design.

Patented Nov. 9, 1915.

Application filed April 27, 1915. Serial No. 24,359. Term of patent 7 years.

To all whom it may concern:

Be it known that I, ZOE ARMSTRONG, a citizen of the United States, residing at McPherson, in the county of McPherson and State of Kansas, have invented a new, original, and ornamental Design for Pans, of which the following is a specification, reference being had to the accompanying drawing, forming a part thereof.

Figure 1 is a side elevation of a pan, showing my new design; and Fig. 2 is a plan view thereof.

I claim:

The ornamental design for a pan, as shown.

ZOE ARMSTRONG.
